UNITED STATES PATENT OFFICE.

LEOPOLD STERNBERGER, OF PHILADELPHIA, PENNSYLVANIA.

BELT-SHIFTING MECHANISM FOR WASHING-MACHINES.

SPECIFICATION forming part of Letters Patent No. 234,439, dated November 16, 1880.

Application filed August 30, 1880. (No model.)

To all whom it may concern:

Be it known that I, LEOPOLD STERNBERGER, of the city and county of Philadelphia, in the State of Pennsylvania, have invented 5 certain new and useful Improvements in Belt-Shifting Mechanism for Washing-Machines, of which improvements the following is a specification.

My invention is specially designed for use 10 in connection with the washing-machine for which an application for Letters Patent of the United States was filed by me under date of October 7, 1879, but by proper modifications of constructive detail is likewise applicable to 15 other purposes.

The object of my invention is to provide 20 simple and efficient mechanism for starting and stopping a rotatable washing-vessel; and to this end my improvements consist in the combination of a shaft and a brake-drum secured thereon, a belt-shifter, a friction-brake, an operating-lever, and a rock-shaft and arms for simultaneously actuating the shifter and brake, all as hereinafter more fully set forth.

25 In the accompanying drawings, Figure 1 is an end view, in elevation, of a washing-machine embodying my improvements; Fig. 2, a side view, in elevation, of the same; and Fig. 3, a view, in perspective, of the stopping and 30 starting mechanism detached.

My improvements are herein shown as applied in the washing-machine which is set forth in my application for Letters Patent hereinbefore referred to.

35 The cylindrical washing-vessel A is secured upon a shaft, B, which is rotatable in bearings in a frame, B', and carries a spur-gear, C³, meshing with a pinion, d, on a counter-shaft, D.

The counter-shaft D carries a fast pulley, D', 40 and a loose pulley, D², and a driving-belt from a main or line shaft is shifted from the loose to the fast pulley, or vice versa, according as it is desired to rotate or to stop the movement of the vessel, by shifting-arms e, secured upon 45 a bar, E, which slides in guides e' upon the frame of the machine, and is operated simultaneously with a friction-band, F, encircling a brake rim or drum, C², secured upon the shaft B, by a sliding bar or rod, E', which is 50 connected at one end by a bell-crank, e², with the bar E, and is provided at the other end with a proper handle or lever, by which it may be moved.

In the instance shown the end opposite that

to which the bar E is connected is coupled by 55 a bell-crank, e³, with a bar or rod, e⁴, having a handle upon its opposite end, and which may, if desired, have a segment-lever and catches for holding it in desired position, the object of employing the bar e⁴ being, for the 60 sake of convenience, to enable the operator to start and stop the machine from the end opposite that adjacent to which the mechanism is located.

A pin, e⁵, upon the bar E' enters a slot in 65 the upper end of one arm, e⁶, of a rock-shaft, e⁷, which is mounted in a bearing on the frame B' of the machine, and carries two arms, e⁸ e⁹, to which the ends of the friction-band F are respectively connected. 70

By the vibration of the rock-shaft induced by the movement of the bar E' to the left in Fig. 1 (which movement shifts the driving-belt from the fast to the loose pulley) the friction-band F is pressed against the face of the 75 brake-rim C², and the movement of the vessel A is arrested coincidently with the cessation of the application of driving-power to the counter-shaft D, and conversely the friction-band is released from the brake-rim coincidently with the movement of the bar E' to the right to apply power to the counter-shaft. 80

I claim as my invention and desire to secure by Letters Patent—

1. The combination, with a shaft, a brake-drum attached thereto, and a friction-band encircling said brake-drum, of a belt-shifter, a sliding bar or rod for operating said belt-shifter, a bell-crank connecting the belt-shifter and sliding bar, and a triple-armed rock-shaft, 85 having two of its arms connected, respectively, to the ends of said friction-band, and the third to the operating-bar of the belt-shifter, the combination being and operating substantially as set forth. 90

2. The combination of a sliding bar carrying belt-shifting arms, an operating bar or rod, a bell-crank connecting said sliding and operating bars, and a rock-shaft having one long and two short arms, the long arm being 100 slotted to receive a pin upon the said operating-rod, and the two short arms being adapted for connection to the ends of a friction-band, substantially as set forth. 95

L. STERNBERGER.
